[57] CLAIM

The ornamental design for a paint roller cleaner, substantially as shown and described.

DESCRIPTION

FIG. 1 is a front elevational view of a paint roller cleaner, showing my new design.

FIG. 2 is a left side elevational view thereof, with the tubing broken away for clarity.

FIG. 3 is a right side elevational view thereof with the tubing broken away for clarity.

FIG. 4 is a rear elevational view thereof, with the tubing broken away for clarity.

FIG. 5 is a fragmentary cross-sectional view taken along the plane of line 5—5 of FIG. 4.

FIG. 6 is a top view thereof, with the tubing broken away for clarity.

FIG. 7 is a bottom view thereof, with the tubing broken away for clarity.
